VARIABLE-DISPLACEMENT RADIAL-PISTON PUMP

Tony M. Moulden, Montrose, Calif.

Application November 26, 1948, Serial No. 62,026

3 Claims. (Cl. 103—161)

1

My invention relates in general to rotary pumps and, more particularly, to a device of the type having radially movable pistons for pumping fluid, a primary object of the invention being to provide a variable displacement pump of this general character.

More specifically, an object of the present invention is to provide a pump having a main rotor which is provided with a plurality of substantially radially movable pistons, and having an auxiliary rotor to which the pistons are connected and which is rotatable about an auxiliary axis substantially parallel to and spaced from the axis of rotation of the main rotor so as to reciprocate the pistons in their respective cylinders during rotation of the main and auxiliary rotors.

Another object of the invention is to provide such a pump with a housing having an inlet port for admitting a fluid to be pumped into the cylinders during inward movement of the pistons therein, and having an outlet port for receiving pumped fluid discharged from the cylinders as the pistons move outwardly therein.

An important object of the invention is to provide a pump of the foregoing general character having means for shifting the auxiliary rotor laterally with respect to the main rotor so as to vary the stroke of the pistons in their respective cylinders, whereby to vary the displacement of the pump.

Another object is to provide such a pump having means for shifting the auxiliary rotor from an inoperative position wherein the auxiliary axis coincides with the axis of rotation of the main rotor and wherein the displacement of the pump is zero to an operative position wherein the auxiliary axis is spaced from the axis of rotation of the main rotor and wherein the displacement of the pump is greater than zero.

Another object is to provide means for shifting the auxiliary rotor between inoperative and operative positions in a plane.

A further object is to provide a pump of the foregoing character having cam means for shifting the auxiliary rotor and having actuating means for operating the cam means.

Another important object is to provide a cam means for shifting the auxiliary rotor which comprises a pair of annular eccentric disposed one within the other.

Another object is to provide such a cam means wherein the eccentric are rotatable from an inoperative position wherein they are in opposition to an operative position wherein they are in apposition so as to shift the auxiliary rotor from

2

its inoperative position wherein the auxiliary axis coincides with the axis of rotation of the main rotor to an operative position wherein the auxiliary axis is spaced its maximum distance from the axis of rotation of the main rotor, whereby to vary the displacement of the pump from zero to its maximum value.

Another object of the invention is to provide a pump wherein the aforementioned actuating means comprises lever means for rotating the annular eccentric in synchronism from an inoperative position wherein they are in opposition to an operative position wherein they are in apposition so as to shift the auxiliary rotor in a plane.

Another object is to provide such a pump having means responsive to fluid pressure in the outlet port for operating the actuating means in a manner to maintain the pressure in the outlet port substantially constant.

The foregoing provides a variable-displacement, constant pressure pump, which is another important object of the invention.

The foregoing objects of my invention and the advantages suggested thereby, together with various other objects and advantages which will become apparent, may be attained through the employment of the exemplary embodiment of the invention which is illustrated in the accompanying drawing and which is described in detail hereinafter. Referring to the drawing:

Fig. 1 is an end elevational view of a pump embodying the invention with part of the pump in section;

Fig. 2 is a longitudinal sectional view taken along the broken line 2—2 of Fig. 1;

Fig. 3 is a transverse sectional view taken along the broken line 3—3 of Fig. 2 and showing the pump set for zero displacement, and;

Fig. 4 is a view similar to Fig. 3 and showing the pump set for a displacement greater than zero.

Referring to the drawing, I show a housing 10 having a chamber 11 therein and having spaced inlet and outlet ports 12 and 13 which extend circumferentially of and communicate with the chamber. Disposed within the housing 10 and rotatable about a main axis A—A is a main rotor 14 which is provided with a plurality of cylinders 15, the latter extending substantially radially from the main axis and having pistons 16 reciprocably disposed therein. The pistons 16 are pivotally connected to an auxiliary rotor 17 which is disposed within the main rotor 14 in the particular construction illustrated, and

which is rotatable about an auxiliary axis B—B, the auxiliary rotor being shiftable laterally with respect to the main rotor between an inoperative position, shown in Figs. 1 to 3 of the drawing, wherein the auxiliary axis B—B coincides with the main axis A—A, and various operative positions, one of which is shown in Fig. 4 of the drawing, wherein the auxiliary axis is spaced from the main axis. The device also includes cam means 18 for shifting the auxiliary rotor 17 between its operative and inoperative positions, actuating means 19 for operating the cam means, and means 20 responsive to fluid pressure in the outlet port 13 for operating the actuating means.

Considering the device in more detail, the housing 10 is provided with inlet and outlet bosses 22 and 23 having bores 24 and 25 therethrough which respectively communicate with the inlet and outlet ports 12 and 13, the respective bosses 22 and 23 being provided with counterbores 26 and 27 to receive inlet and outlet pipes (not shown), or the like. Connected to one end of the housing 10 by bolts 30 is a bracket 31 by means of which the device may be mounted on a suitable supporting structure, the bracket being provided with holes 32 for mounting bolts (not shown), or the like. The opposite end of the housing 10 is provided with a recess 33 for the actuating means 19, a cover plate 34 for the recess 33 being connected to the housing by means of bolts 35.

Disposed within the chamber 11 in the housing is an annular liner 38 which defines a rotor chamber 39, the liner having a plurality of apertures 40 which provide fluid communication between the rotor chamber and the inlet and outlet ports 12 and 13. The main rotor 14 is disposed in the rotor chamber 39 and includes an annular disc 41 which encircles the auxiliary rotor 17, the cylinders 15 extending through the annular disc in radial directions with respect to the main axis A—A. The outer periphery of the annular disc 41 makes substantially fluid-tight contact with the inner periphery of the liner 38, i. e., the peripheral wall of the rotor chamber 39 and the sides of the annular disc engage thrust rings 42. Any fluid leaking between the annular disc 41 and the liner 38 on the high pressure side of the pump flows to the low pressure side thereof through clearances provided between the sides of the annular disc and the side walls of the rotor chamber 39, as best shown in Fig. 2 of the drawing.

The main rotor 14 includes a main shaft 45 which is formed integrally with the main rotor in the particular construction illustrated and the axis of which coincides with the main axis A—A, the shaft 45 extending through bearings 46 which are disposed in a counterbore 47 in the housing 10 and which are separated by a bearing spacer 48. A shaft seal 49 for preventing leakage from the rotor chamber 39 along the shaft 45 encircles the shaft and is disposed in a counterbore 50 in the housing 10. The shaft 45 extends through a bore 51 in the housing 10 and is provided with means 52 for connection to any suitable device (not shown) for driving the main rotor 14, the means 52 comprising a socket formed in the outer end of the shaft in the particular construction illustrated.

The auxiliary rotor 17 comprises a master rod 55 which is carried by a shaft means comprising an auxiliary shaft 56, the latter being provided with thrust collars 57 respectively engaging opposite sides of the master rod. Preferably, an

annular bearing insert 58 is disposed between the master rod 55 and the auxiliary shaft 56. As best shown in Figs. 3 and 4 of the drawing, the master rod is pivotally connected to one of the pistons 16, and the remaining pistons are pivotally connected to the master rod by the link rods 59.

As best shown in Figs. 1 and 2 of the drawing, the auxiliary shaft 56, the axis of which coincides with the auxiliary axis B—B, is carried by a bearing 62 which is retained on the auxiliary shaft between one of the thrust collars 57 and a washer 63 by a nut 64.

Considering the operation of the pump as thus far described, it will be apparent that rotation of the main shaft 45 will result in rotation of the main and auxiliary rotors 14 and 17, rotation of the main motor being communicated to the auxiliary rotor through the pistons 16 and the connections between the pistons and the auxiliary rotor. As long as the auxiliary rotor is in its inoperative position, i. e., the position shown in Figs. 1 to 3 of the drawing, wherein the auxiliary axis B—B coincides with the main axis A—A, the pistons 16 remain stationary in the cylinders 15 so that no fluid is displaced from the inlet port 12 to the outlet port 13. In other words, with the auxiliary rotor 17 in its inoperative position, the displacement of the pump is equal to zero.

However, if the auxiliary rotor 17 is shifted laterally with respect to the main rotor 14 by the cam means 18 into an operative position, such as that shown in Fig. 4 of the drawing, wherein the auxiliary axis B—B is spaced from the main axis A—A, the pistons 16 will reciprocate in their cylinders 15 as the main and auxiliary rotors rotate in the direction of the arrow 65 in Fig. 4 of the drawing so as to displace fluid from the inlet port 12 to the outlet port 13. In other words, if the auxiliary rotor 17 is shifted relative to the main rotor 14 in the direction shown in Fig. 4 of the drawing, rotation of the main and auxiliary rotors in the direction of the arrow 65 will result in inward movement of the pistons 16 during the interval that their cylinders are in communication with the inlet port 12 and will result in outward movement of the pistons during the interval that their cylinders are in communication with the outlet port 13. Thus, each piston 16 draws a charge of fluid into its cylinder from the inlet port 12 during the interval that its cylinder is in communication with the inlet port, and discharges the charge of fluid into the outlet port 13 during the interval that its cylinder is in communication with the outlet port. It will be apparent that the stroke of the pistons 16, and, consequently, the displacement of the pump, are dependent on the distance that the auxiliary axis B—B is shifted from the main axis A—A. In other words, the displacement of the pump is zero when the auxiliary axis B—B coincides with the main axis A—A, and is a maximum when the auxiliary axis is spaced from the main axis the maximum distance. As will be apparent, the displacement of the pump may be varied between zero and the maximum value by varying the spacing between the axes A—A and B—B by means of the cam means 18.

As will be discussed in more detail hereinafter, the cam means 18 is adapted to move the auxiliary axis B—B in a plane, which is indicated by the broken line C—C, so as to maintain the proper relation between the inlet and outlet ports 12 and 13 and the positions of the pistons

16 in their cylinders 15. The pistons attain their top and bottom dead center positions with respect to the main rotor 14 as they traverse the plane C—C and this plane is so oriented that the pistons attain their top and bottom dead center positions during the intervals that their cylinders move from positions wherein they communicate with one of the ports 12 or 13 to positions wherein they communicate with the other of these ports. Preferably, the ports 12 and 13 lie on opposite sides of and equidistant from the plane C—C.

Considering the cam means 118 in more detail, it comprises inner and outer annular eccentrics 71 and 72, the inner eccentric being mounted on the bearing 62 which carries the auxiliary shaft 56 and the outer eccentric being mounted on the inner. The outer eccentric 72 is journaled in an annular bearing 73 which is disposed in a bore 74 in the housing 10, and the inner eccentric 71 is journaled in an annular bearing 75 disposed between the two eccentrics. Although the bearings 73 and 75 have been exemplified as being of the bushing type, it will be apparent that any suitable type of bearing may be employed.

It will be apparent that rotation of either or both the eccentrics 71 and 72 from the positions shown in Fig. 1 of the drawing will result in lateral shifting of the auxiliary rotor 17 with respect to the main rotor 14. However, as indicated previously, it is necessary to shift the auxiliary rotor 17 in a predetermined plane, such as the plane C—C, in order to maintain the proper relation between the inlet and outlet ports 12 and 13 and the positions of the positions 16, and this is accomplished by rotating the two eccentrics in synchronism between the positions shown in Fig. 1 of the drawing, wherein the eccentrics are in opposition, and positions (not shown) wherein the eccentrics are in apposition. The eccentrics 71 and 72 may be said to be in opposition when the lobes thereof, i. e., the positions thereof of greatest radial thickness, are opposite each other, and may be said to be in apposition when the lobes thereof are in registry. As will be apparent, when the eccentrics 71 and 72 are in opposition, the auxiliary axis B—B coincides with the main axis A—A, and when the eccentrics are rotated toward the positions wherein they are in apposition, the auxiliary rotor 17 is shifted laterally with respect to the main rotor to space the auxiliary axis from the main axis. In other words, when the eccentrics 71 and 72 are in opposition, the displacement of the pump is equal to zero, and when the eccentrics are in apposition, the displacement of the pump is a maximum. As will be apparent, if the eccentrics are rotated from opposition into apposition in synchronism, i. e., at the same angular speed, shifting of the auxiliary motor 17 with respect to the main rotor 14 will take place in the plane C—C as hereinbefore indicated.

Considering the actuating means 19 for rotating the eccentrics 71 and 72, it comprises a lever 78 which is pivotally connected to the housing 10 at 79, and comprises a lever 80 which is pivotally connected to the housing at 81, the levers 78 and 80 being pivotally interconnected intermediate their respective ends by a pin 82 which is movable in a slot 83. The lever 78 is connected to the eccentric 72 by a link 85, the latter being pivotally connected to the lever 78 at 86 and being pivotally connected to the eccentrics 72 at 87. Similarly, the lever 80 is connected to the eccentric 71 by a link 88, the latter being

pivotally connected to the lever 80 at 89 and being pivotally connected to the eccentric 71 at 90.

As will be apparent, counterclockwise rotation 5 of the lever 78, as viewed in Fig. 1 of the drawing, will result in counterclockwise rotation of the eccentric 72, and will result in clockwise rotation of the lever 80, clockwise rotation of the latter resulting in clockwise rotation of the eccentric 71. Thus, rotation of the lever 78 about its pivot 79 results in rotation of the eccentric 71 and 72 in opposite directions. The relation between the various components of the actuating means 19 is such that the eccentric 71 and 72 10 are rotated in opposite directions in synchronism so as to shift the auxiliary rotor 17 in the plane C—C as hereinbefore discussed. The positions of the pivots 87 and 90 when the eccentrics 71 and 72 15 are in apposition are shown in phantom in Fig. 1 of the drawing and are respectively identified by the numerals 87' and 90'.

Although the actuating means 19 may be operated in any suitable manner, such as manually, to vary the displacement of the pump in the 20 manner hereinbefore discussed, I prefer to provide the pump with the pressure responsive means 20 for operating the actuating means in a manner to maintain the pump outlet pressure at a substantially constant value. Considering 25 the pressure responsive means 20 in more detail, it comprises a piston 93 which is connected to the lever 78 by a ball and socket joint 94 and which is reciprocable in a cylinder 95. One end of the piston 93 is exposed to the fluid pressure 30 obtaining in the outlet port 13 by connecting the corresponding end of the cylinder 95 to the outlet port in any suitable manner, as by a tube 96. Seated against the opposite end of the piston 93 is a spring 97 which is retained in the cylinder 95 by a plug 98.

It will be apparent that, with the foregoing 35 construction, if the outlet pressure rises above a predetermined value for any reason, the piston will move downwardly, as viewed in Fig. 1 of the drawing, to operate the actuating means 19 in a manner to rotate the eccentrics 71 and 72 toward positions wherein they are in opposition so as to decrease the displacement of the pump to compensate for the increased outlet pressure. Conversely, if the outlet pressure decreases below a predetermined value, the piston 93 will move 40 upwardly to rotate the eccentrics 71 and 72 toward positions wherein they are in apposition so as to increase the displacement of the pump to compensate for the reduced outlet pressure. As will be apparent, such variations in outlet 45 pressure may arise from variations in the load on the pump.

It will thus be apparent that my invention 50 provides a variable displacement pump which, by utilizing the pressure responsive means 20, may be employed to provide constant pressure output, which is an important feature of the invention.

Although I have disclosed an exemplary embodiment of my invention herein for purposes of illustration, it will be understood that I do not intend to be limited specifically thereto since various changes, modifications and substitutions 55 may be incorporated in the particular embodiment disclosed without necessarily departing from the spirit of the invention.

I claim as my invention:

1. In a device of the character described, the 60 combination of: a housing having an inlet port

and an outlet port; a rotor in said housing and rotatable about a main axis, said rotor having a plurality of substantially radial cylinders; means for connecting said cylinders to said inlet and outlet ports in sequence as said rotor rotates; a plurality of pistons respectively reciprocable in said cylinders; shaft means providing an auxiliary axis substantially parallel to said main axis and shiftable laterally relative to said rotor between an inoperative position wherein said auxiliary axis substantially coincides with said main axis and an operative position wherein said auxiliary axis is spaced from said main axis; means for pivotally connecting said pistons to said shaft means; and means for shifting said shaft means between said operative and inoperative positions, the shifting means including cam means operatively connected to said shaft means, a control cylinder carried by said housing, a control piston reciprocable in said control cylinder, passage means connecting said outlet port to one end of said control cylinder so that pressure variations in said outlet port result in movement of said control piston in said control cylinder, and means connecting said control piston to said cam means.

2. In a device of the character described, the combination of: a housing having an inlet port and an outlet port; a rotor in said housing and rotatable about a main axis, said rotor having a plurality of substantially radial cylinders; means for connecting said cylinders to said inlet and outlet ports in sequence as said rotor rotates; a plurality of pistons respectively reciprocable in said cylinders; shaft means providing an auxiliary axis substantially parallel to said main axis and shiftable laterally relative to said rotor in a plane between an inoperative position wherein said auxiliary axis substantially coincides with said main axis and an operative

position wherein said auxiliary axis is spaced from said main axis; means for pivotally connecting said pistons to said shaft means; an inner annular eccentric rotatable on said shaft means; an outer annular eccentric rotatable on said inner eccentric; and actuating means for rotating said eccentric in synchronism to shift said shaft means in said plane between said operative and inoperative positions, including a first lever pivotally connected to said housing, including a second lever pivotally connected to said housing, including means for pivotally connecting said first lever to said second lever, including means for pivotally connecting said first lever to one of said annular eccentric, including means for pivotally connecting said second lever to the other of said annular eccentric, and including means for rotating said first lever about its pivotal connection to said housing.

3. A device as set forth in claim 2 wherein the means last defined includes means exposed to and responsive to pressure variations in said outlet port.
